UNITED STATES PATENT OFFICE

157,088

HINGED BRACKET OR SIMILAR ARTICLE

William M. Reithard, Los Angeles, Calif., assignor to Link Anderson, Inc., Santa Monica, Calif., a corporation of California

Application May 3, 1948, Serial No. 146,136

Term of patent 14 years

(Cl. D10—9)

To all whom it may concern:

Be it known that I, William M. Reithard, a citizen of the United States, residing at Los Angeles, in the county of Los Angeles and State of California, have invented a new, original, and ornamental design for a Hinged Bracket or Similar Article, of which the following is a specification, reference being had to the accompanying drawing, forming a part thereof.

I claim:

The ornamental design for a hinged bracket or similar article, substantially as shown.

WILLIAM M. REITHARD.
